TELEVISION RECEIVING CONNECTION

Kurt Schlesinger, Berlin, Germany, assigner, by
mesne assignments, to Loewe Radio, Inc., a cor-
poration of New York

Application November 20, 1935, Serial No. 50,739
In Germany November 22, 1934

2 Claims. (Cl. 178—7.3)

The invention relates to television receiver circuits, more particularly to filter arrangements to separate the synchronising impulses from the image current.

- 5 The invention relates to television receivers for co-operation with a television transmitter in which the carrier wave of the transmitter is reduced to zero in the case of, and only in the case of, the synchronisation signals.
- 10 In the drawing Figs. 1a and 1b show a diagram of the intensities in the image circuit of a television receiver.

Fig. 2 shows an amplitude filter circuit connected to the ultra-short wave audion stage by 15 a coupling condenser.

In Fig. 3 there is provided instead of the coupling condenser a D. C. coupling.

If a transmission of this nature is picked up by a receiver which can accommodate all frequencies, including the D. C. components, and if condenser couplings are not provided in the receiver circuit, up to the cathode ray tube, a diagram of amplified received signals has the appearance of Fig. 1a for powerful and Fig. 1b for weak reception. The invention relates to the amplitude filter, which has the known function of separating the synchronisation peaks 1 from the image current 2. Difficulties occur in practice due to variation in the sensitivity of the 20 receiver or variation in the strength of the received signal due to fading. Fig. 2 illustrates the reason for these difficulties and shows the final rectifier of an intermediate-frequency amplifier, viz., a twice grid detector whose grids are 25 coupled with the intermediate-frequency transformer 3 and whose anode resistance is directly coupled to the grid electrode of the Braun tube 6. If an amplitude filter, for example a glow 30 discharge tube 8, is coupled with the lead 5 through a condenser 7, it is possible to impart 35 to the cathode 9 of this tube through the leakage resistance 16 a positive bias of such amount that a correct separation of the synchronisation signals is effected for a certain definite received 40 strength of signal so that the glow discharge tube 8 in the anode circuit passes to the transformer 12 the synchronisation signals and nothing more. This bias 11, however, should be varied continuously in accordance with the variation 45 in the strength of the signals, and the use of a condenser 7 means that the glow discharge tube is excited by alternating potentials, which rise and fall in proportion to the strength 50 of the received signals. An amplitude filter of this nature marks in effect in Figs. 1a, 1b a di-

viding line, which may be adjusted to any fixed value by the battery 11. This dividing line in the case of a powerful signal should be situated in Fig. 1a at the level designated 13a, and in the case of a weak signal (Fig. 1b) its height should be to smaller extent above the zero line, and it is designated 13b.

Such a variation of the bias of the amplitude filter 8 in accordance with the received signal strength is possible by means which are known per se, but such a method represents a considerable difficulty and is accompanied by the danger of failure, as it may readily occur that an automatically regulated bias of this kind is too small and in consequence allows also image signals to pass through the glow discharge tube 8, in the same manner as it may also readily be the case that the bias is too high and accordingly does not allow any signals at all to reach the transformer 12. If a variable bias of this kind is to be avoided, i. e., replaced by a fixed direct potential, it is apparently only possible to adopt the course of maintaining the signal strength constant at the resistance 4. The methods necessary for this purpose are well known in the radio art as fading compensation methods. In this case they would preferably consist in the fact that the amplitude of the separated synchronisation signals is utilised or the D. C. mean value thereof as regulating potentials. This method, however, is also very artificial and not sufficiently reliable.

The invention consists of a method differing from those referred to, and is based on the idea that a direct coupling is introduced between the amplitude filter 8 and the connecting resistance 4.

Fig. 3 serves for explanation. It again shows the anode circuit 4 of the final detector 15, which is directly coupled with the grid lead 5 of the television tube 6. According to the invention, the cathode 9 of the filter tube 8 is connected with this lead 5 directly, i. e., not through the medium of condensers, while from a potentiometer 14, which is connected in parallel to the anode potential source 27 of the detector 15, there is conducted to the anode of the tube 8 via the output transformer or transformers 12, 12' a bias of such extent that a stream of electrons is able to flow through the tube 8 only when the carrier wave completely ceases, i. e., upon maximum current value of the detector and in a very small potential range above the value zero of the carrier. As well known, the detector as shown has the property of providing

a maximum current when the reception ceases. In the curves in Fig. 1 the new threshold which remains constant independently of the strength of the reception is shown in broken lines in both 5 figures at the same level and designated 14'. It will be clearly recognisable that only the shaded potential values which are situated between this level 14' and the zero line in the reception diagram are capable of being passed through the 10 filter tube 8, immaterial of the strength to which the reception is otherwise adjusted. The filter circuit accordingly deals only with the maxima of the synchronisation signals, and separates a constant potential range proceeding from the 15 maximum, whilst in known connections the line of separation was disposed at the bounding line between image and synchronisation signals and in consequence the filter signals were of greatly varying amplitude and moreover difficulties were 20 encountered in obtaining a clean limited curve between image and synchronisation signals. An additional advantage of the new method consists in the fact that the position of the zero line at which the reception disappears is completely independent of the adjustment of any amplifying 25 tubes of the receiver, and is only dependent on the biases of the final rectifier, with which the filter tube is directly coupled. According to the invention, there are selected output detector 30 circuits which operate with zero grid bias, which is the case for example for that shown in the drawing, as connections of this detector offer the greatest guarantee that the adjusted level will not again vary in the course of time. Furthermore, according to the invention, the 35 potentiometer 14 is made to be operable from the outside of the apparatus, in order to be able to adjust the strength of the synchronisation signal once and for all to the optimum amount 40 which acts reliably on the relaxation apparatus but does not overload the same. The fact that the separated peaks of the synchronisation signals do not contain a remainder of carrier frequency, as no further carrier frequency is transmitted, facilitates accurate synchronisation and 45 represents an additional advantage as compared with methods which make use of separating lines such as 13a, 13b.

By reason of the direct coupling with the filter 50 according to the invention the independence of the synchronisation from the intensity of the received signal is definitely solved. The adjustment of the intensity of the received signal may accordingly take place independently thereof by 55 special means. It is even proposed according to the invention to regulate the amplitude of the signal output by means of a circuit or a special diode which has no further connection with the synchronisation circuit illustrated in Fig. 3, and 60 in particular is not capable of interfering with the bias 14.

I claim:

1. In a television receiving system wherein picture and synchronizing signals are received as a modulation of a common carrier and wherein the carrier amplitude reaches a substantially fixed predetermined level for the synchronizing signals comprising a detector having a cathode, a control electrode and an output electrode, means for applying the picture and synchronizing signals to be detected between the control electrode 10 and the cathode of said detector, means including an impedance for maintaining the detector output electrode positive with respect to the cathode, a synchronizing signal separator tube including a cathode and an output electrode, 15 means for directly connecting the cathode of the separator tube to the output electrode of the detector tube, and means for normally maintaining the output electrode of the separator tube negative with respect to its associated cathode 20 by a voltage difference of such magnitude that current will be passed by the separator tube only during the intervals that synchronizing signals are received whereby all synchronizing signals in excess of a substantially constant predetermined 25 amplitude are separated from the picture signals irrespective of the strength of the picture signals.

2. In a television receiving system wherein picture and synchronizing signals are received as a modulation of a common carrier and wherein the carrier amplitude reaches a substantially fixed predetermined level for the synchronizing signals and wherein said synchronizing signals are of a predetermined duration following each train of 30 picture signals for each scanned line and of a different predetermined duration following successive trains of picture and line synchronizing signals to represent each scanned picture field comprising a detector having a cathode, a control electrode and an output electrode, means for applying the picture and synchronizing signals to be detected between the control electrode and the cathode of said detector, means including an impedance for maintaining the detector output 35 electrode positive with respect to the cathode, a synchronizing signal separator tube including a cathode and an output electrode, means for directly connecting the cathode of the separator tube to the output electrode of the detector tube, 40 and means for normally maintaining the output electrode of the separator tube negative with respect to its associated cathode by a voltage difference of such magnitude that current will be passed by the separator tube only during the 45 intervals that synchronizing signals are received whereby all synchronizing signals in excess of a substantially constant predetermined amplitude are separated from the picture signals irrespective of the strength of the picture signals.
